UNITED STATES PATENT OFFICE

107,328

DESIGN FOR A COMBINED CURTAIN ROD AND SHADE ROLLER BRACKET

Henry W. Ullrich, Elizabeth, N. J.

Application June 4, 1937, Serial No. 69,673

Term of patent 14 years

To all whom it may concern:

Be it known that I, Henry W. Ullrich, a citizen of the United States, residing at 622 Madison Avenue, Elizabeth, New Jersey, have invented a new, original, and ornamental Design for a Combined Curtain Rod and Shade Roller Bracket, of which the following is a specification, reference being had to the accompanying drawing, forming a part thereof.

The figure is a perspective view of the combined curtain rod and shade roller bracket showing my new design.

I claim:

The ornamental design for a combined curtain rod and shade roller bracket as shown.

HENRY W. ULLRICH.
